UNITED STATES PATENT OFFICE

CLARENCE F. MILES, OF WORCESTER, MASSACHUSETTS

COORDINATE HARMONICA PLAYER

Application filed August 18, 1931. Serial No. 557,755.

This invention relates to an attachment for harmonicas.

The principal objects thereof are to provide a simple and inexpensive device to be applied to a harmonica for simplifying the technique of tonguing the harmonica; to provide a means for simplifying the playing of a single melody note or two melody notes a perfect interval apart so that the chords sounded when playing melodies, when using the device, in the different major diatonic scales of the different major diatonic harmonicas will harmonize with the melody which is being played; to provide a device for this purpose which will not only be very simple to construct and to use, but will have the means for preventing the escape of air and means by which the harmonica will slide easily with respect to the device, so that the position of the device while being held in the mouth will be stationary and the lips nearly stationary on the device, while the harmonica itself is being moved lengthwise in the device.

Other objects and advantages of the invention will appear hereinafter.

Reference is to be had to the accompanying drawings, in which

Fig. 1 is a front view of a preferred embodiment of this invention applied to a harmonica;

Fig. 2 is a side view of the same;

Fig. 3 is a transverse sectional view on the line 3—3 of Fig. 1, showing the harmonica in dotted lines, and

Fig. 4 is a sectional view on the line 4—4 of Fig. 3.

The device itself is very simple and can be applied to a harmonica of the form shown or modified slightly to enable it to be applied to any other form of harmonica. It consists simply of a member 10 which is symmetrical and is provided with two flanges 11 on opposite sides of the harmonica shaped to fit the outside surface except that a lining of felt 12 can be employed, if desired, on the inside of each flange and on the member.

The playing part 13 is of considerable thickness to prevent the chance of the lips or the tongue of the player from coming in

contact with the harmonica itself or being pinched and cut between the attachment and the harmonica. This part is provided with one or more, preferably one, felt pads 14 with openings 15 pinched in them in line with the holes in the device. The felt pads 14 are located on the under side for engaging the harmonica, and preventing the escape of air. These pads are located in grooves on the inner side of the attachment.

There are five of these openings 15 spaced apart as will be described and four slight rounded projections 16 are employed on both sides of each of the outside openings 15.

As stated in the description, it is of a strictly one-piece construction except for the felt lining to produce an air-tight construction and a smoothly sliding arrangement and also prevent vibration. This felt is attached to the inside surface of the device by cement or other means. The five openings are used when the device is made for use with the major diatonic so-called single reed ten-hole harmonica and are used to produce melody in the two upper melody octaves of the harmonica and extend into the bass of the harmonica when so desired. When made for other types of harmonicas it will be modified accordingly, using the same principle, as described. These five openings are equally spaced apart, the same as the ten holes in the harmonica and of course will cover exactly any series of five holes, in the harmonica.

When using the device and drawing the breath to sound notes in the harmonica any series of five of the ten holes in the harmonica can be sounded. According to the diatonic scale arrangement of the major diatonic single key harmonica, the end holes will sound perfect intervals an octave, or perfect interval part. The three intervening notes sounded between the perfect interval end notes that are sounded when drawing only, are used for the time accompaniment. This is accomplished by beating the end of the tongue upon them to the time of the melody in conjunction with the drawing of the breath, that is, they are utilized for time accompaniment in conjunction with the sounding of the melody notes when drawing

the breath. The whole procedure makes a combination producing one or two, at the will of the performer, melody notes; melody, harmony chords and time accompaniment.

5 When using the device and blowing the breath to sound notes in the harmonica, any series of five of the ten holes in the harmonica can be sounded, but the lips at either corner of the mouth are now contracted at 10 one end of the device via one set of indicating nubs so that only four of the five openings in the device can permit the passage of the breath blown into the harmonica. Thus, according to the diatonic scale arrangement 15 of the major diatonic single key harmonica, the end notes of the four holes in the device, when blowing only, will be notes in perfect intervals to each other an octave apart. In this case the two intervening notes are used 20 for time accompaniment as stated before, the whole procedure, when blowing and drawing and making melody via the device on a diatonic harmonica, making a combination producing one melody note or two perfect intervals at the will of the performer, melody notes, melody, harmony, chords and time accompaniment.

It can be seen readily that when blowing the breath to sound two perfect interval notes 30 an octave apart, the device must be instantly transformed from a five hole device into a four hole device to be able to sound, via the major diatonic scale arrangement of the harmonica, two perfect interval notes an 35 octave apart, when blowing only, and when drawing vice versa. The contracting movement of the lips at one corner of the mouth serve this purpose. By the simplicity of this design or arrangement of this invention, it 40 will be readily seen that mechanical valves, springs serving as valves, air by-paths, sliding slots, etc. are automatically eliminated.

In both procedures of blowing or drawing 45 for melody, if desired, only one high or low melody note may be sounded at a time while blowing or drawing the breath through only one end hole of the device and the remaining notes higher or lower sounded may be used for time accompaniment or only one note at 50 a time sounded to produce the melody, via the tongue, breath, time of melody, etc. When blowing or drawing the breath via the device and sounding only one of the notes of the harmonica at a time arpeggios 55 may be played.

This attachment or device can be made of metal, aluminum, celluloid, hard rubber, bakelite or other suitable material. It is formed to somewhat resemble the outside 60 of a harmonica and its top is practically the same as the top of a harmonica, except that it is somewhat longer, for proper bearing surface for the harmonica when playing in the bass or high octave. It has, as stated, less 65 blow holes. The top is made of thick con-

struction to prevent the tongue of the performer from becoming pinched and cut between the holes in the top of the harmonica and the holes in the bottom of the top of the attachment. The sides are thinner and, if 70 made of anything except sheet material, they are thicker at the top and thinner at the bottom. They provide a yielding pressure and have enough flexibility or proper clearance, to allow the harmonica to be slid through it 75 easily with or without a lining on the inside of the flanges. There will always be a lining on the flat surface of the device where the blow and draw holes of the device make up with the blow and draw holes of the harmonica. 80

It is provided on each side near the bottom with end holes 17 and with arrows 18 pointing beyond them. These holes provide for 85 visual indication, when desired, to check the position of the reed holes of the harmonica with the position of the holes in the attachment. Through these holes 17, numbers or indicia placed on the harmonica by the manufacturer will show through to thus check the 90 position of the harmonica within the device, whenever this is desired, the arrows point beyond the edge of the device and are a further indication of the position of the harmonica within the device. 95

The four small raised rounded projections 100 on each side of the two end holes on top of the attachment are for the purpose of indicating through the lips of the operator at the corners of the mouth the exact number of 105 blow and draw holes in the device that it is desired to open to the harmonica at any time while playing. In other words, they will indicate to the performer the position of the mouth on the device and the number of openings in the device exposed to the breath. 110

By having the mouth of the player rest upon the device instead of the harmonica the rasping effect of the harmonica upon the lips of the player is eliminated, also the use of 115 saliva upon the harmonica for the purpose of a lubricant is likewise eliminated.

When this attachment is used with this system of employing the breath, tongue and lips, it presents an extremely simplified method of single or double note melody tonguing with time accompaniment. The whole produces melody, harmony, chords and time accompaniment altogether or singly, as desired. With its use it provides ease in playing a single melody note or two perfect interval melody notes an octave apart and the notes between as stated. It also permits the sounding of imperfect intervals closer than a perfect interval. When blowing or drawing in conjunction with the openings in the device, the sounding of melody, chords, harmony and time accompaniment either altogether or singly. Likewise by using only a single hole 125 arpeggios may be played. 130

Although I have illustrated and described only one form of my invention, I am aware of the fact that modifications can be made therein by any person skilled in the art without departing from the scope of the invention as expressed in the claims. Therefore, I do not wish to be limited to all the details of construction herein shown and described, but what I do claim is:—

- 10 1. As an article of manufacture, an attachment for a harmonica consisting of a single piece adapted to be placed over the harmonica and having a plurality of holes, the end ones being spaced an octave apart with respect to the harmonica. 70
- 20 2. As an article of manufacture, an attachment for a harmonica consisting of a single piece of material having two opposite flanges provided with or without a lining engaging and fitting the sides of a harmonica and a central part materially thicker and provided with a number of openings all the way through, spaced at the same distance apart as the blow openings of the harmonica, the 75 two end ones being an octave apart when drawing and one hole less when blowing to complete the octave, and with a lining of soft material for the spaces between and around the ends of the opening on the flush 80 part of the bottom of the top of the device to facilitate the easy sliding of the harmonica in the device and prevent the escape of air being tapered. 85
- 30 In testimony whereof I have hereunto affixed my signature.
- CLARENCE F. MILES.
- 90
- 95
- 100
- 105
- 110
- 115
- 120
- 125
- 130
- 35 3. As an article of manufacture, a harmonica attachment provided with two opposite flanges adapted to fit the sides of a harmonica and a central part of thicker material having five openings therethrough spaced the same as the blow openings of the harmonica and having on both sides of each end opening on the outside of the top of the device a slight projection that will enable and assist the operator in recognizing with his lips the position of his mouth upon the five 45 openings, the part of the attachment beyond the end openings being imperforate and extending substantially throughout the length of the device which is longer than the harmonica. 110
- 40 4. As an article of manufacture, a harmonica attachment provided with two opposite flanges adapted to fit the sides of a harmonica and a central part having openings therethrough spaced the same as the blow 45 openings of the harmonica, the part of the attachment beyond the end openings being imperforate and extending substantially throughout the length of the device, and provided with openings in said flanges through 55 which indicia on the harmonica itself can be observed and arrows in line with the openings and projecting beyond the flanges to enable the position of the harmonica, in the device, to be further registered visually. 115
- 45 5. As an article of manufacture, an attach- 60

ment for a harmonica consisting of a single piece of material having two opposite flanges provided with a lining engaging and fitting the sides of a harmonica and a central part materially thicker and provided with a number of openings all the way through, spaced at the same distance apart as the blow openings of the harmonica, the two end ones being an octave apart when drawing and four openings being an octave apart when blowing and a lining of soft material for the sliding surface on the flush under side of the top of the device where the blow and draw holes of the harmonica make up with the holes of the device to facilitate the easy sliding of 75

the harmonica in the device and prevent the escape of air when it is in the device and in proper registration, said attachment having the bottom and both ends open, the sides being tapered. 80

In testimony whereof I have hereunto affixed my signature.
